SCAFFOLD SUPPORT

Robert E. Goranson, St. Paul, Minn.

Application September 11, 1944, Serial No. 553,535

9 Claims. (Cl. 304—37)

1

My invention relates to an improvement in scaffold support, wherein it is desired to provide a simple and effective means of supporting a scaffold.

In painting or doing repair work it has usually been necessary either to erect a scaffold for supporting the workmen or else to suspend a platform in the proper position. In working upon the exterior of buildings it is often most convenient to suspend a movable platform from the roof of the building. In painting, decorating or repairing the interior of a building it is usually necessary to erect a scaffold upon which the workers may be supported. Such a scaffold takes considerable time to erect and requires considerable floor space. Thus valuable floor space is lost throughout the entire painting or decorating process unless the scaffold is dismantled during working hours which is ordinarily a costly procedure. For this reason painting and decorating is often postponed until it is absolutely necessary.

I have found that vertical columns are often located about the area to be painted or decorated. Most stores for example are provided with regularly spaced pillars which act as building supports. Building walls are often provided with regularly spaced windows leaving vertical pillars therebetween. I have found that by using these existing pillars on building structures as the vertical supports of a scaffolding, a painting and decorating operation may take place without the use of any floor space.

It is an object of the present invention to provide flexible bands encircling spaced posts or pillars and to provide on these bands a means of supporting a scaffold. By using the existing pillars or posts the requirement for a frame work resting on the floor is eliminated, thus greatly simplifying the task of erecting a scaffold. Furthermore, if the room being decorated has a high ceiling the scaffold may be erected and used without requiring any floor space and without interfering with normal operations beneath the scaffold.

A feature of the present invention resides in the fact that the ceiling of a store or office may be often painted without interfering with the normal operation of the store. A platform may be erected substantially above the level of persons in the store and the painting or decorating may continue through the working hours of the day without interference with normal transactions in the store or office.

A feature of the present invention resides in

2

the fact that the flexible bands used to support the scaffold may encircle a pillar or post of virtually any shape and the size of the pillars or posts which act as supports is not particularly important, as long as the band is of sufficient length to encircle the same. Thus it is necessary to support a scaffold from posts or pillars of various sizes and shapes without changing the construction of the supporting elements.

A feature of the present invention resides in the fact that the pillar encircling bands are provided with a clamping means which hold the bands in pillar encircling position. The bands are held in place both by the natural friction of the band and also by the fact that the scaffold is usually supported from one side of the band, thereby tightening the band about its pillar or post as the pressure upon the scaffold increases.

A further feature of the present invention resides in a means of connecting the ends of two scaffold forming members together so as to provide an expandible or contractable scaffold forming element between adjacent posts.

These and other objects and novel features of my invention will be more clearly and fully set forth in the following specification and claims.

In the drawing forming a part of my specification:

Figure 1 is a perspective view of a pair of pillars showing a rigid scaffold supporting element therebetween.

Figure 2 is a sectional view through the clamp for holding the band in encircling position.

Figure 3 is a perspective view of the clamp illustrated in Figure 2.

Figure 4 is a perspective view of the hook which is supported by each band and which acts to support a scaffold member.

Figure 5 is a perspective view of the clamp used to hold the rigid scaffold supporting elements in overlapping relation.

The scaffold support is designed to connect existing pillars or posts of a building in such a manner as to form a support for a scaffold or platform. Figure 1 illustrates a pair of posts or pillars A having scaffold supporting elements B attached thereto. The elements B include a flexible web, belt, or strap 10 having one end 11 thereof attached to a clamping element 12. The other end 13 of each belt 10 is free and may be held in pillar encircling position by means of the clamping element 12.

As best illustrated in Figures 2 and 3 of the drawing the clamping element 12 comprises a box-shaped frame including a rear side 14, a

front side 15, and a pair of top and bottom connecting sides 16. A rectangular frame open at both ends is thus provided.

A clamping plate 17 is slidably supported within the rectangular clamp 12. The clamping plate 17 is provided with a corrugated or otherwise roughened under-surface 19 as best illustrated in Figure 3 of the drawing. The plate 17 extends somewhat beyond the open ends of the frame 12 and is provided with laterally projecting ears 20 which hold the plate in place.

A boss 21 is provided on the exterior surface of the outer plate 15 of the clamping member 12 and a clamping bolt 22 is threaded through this boss 21 and the plate 15. The inner end of the bolt 22 is rounded to engage against the outer surface of the clamping plate 17 so as to press this plate against the band inserted through the clamping element between the plate 17 and the plate 14 of the clamping element. A transverse handle 23 is provided on the bolt 22 to facilitate rotation of the bolt.

A hook element illustrated in general by the numeral 24 is best illustrated in Figures 1 and 4 of the drawing. The hook 24 is provided with a vertical arm 25 which bears against a pillar or post, and the upper extremity of this arm 25 is bent laterally and downwardly at 26 to provide a narrow channel 27 of proper thickness to accommodate the flexible belt B. This channel 27 is only of sufficient thickness to accommodate the belt and provides a means of supporting the hook element 24 from the flexible band.

The element 24 is also provided at its lower end with a laterally extending arm 29 which terminates in an upwardly projecting end 30. The arms 29 and 30 form a hook for accommodating a plank such as a two by six or the like, which is supported on edge to provide maximum strength.

The end 11 of the band 10 is looped about the plate 14 of the clamping element 12 and is secured in this position by rivets 31 or other suitable means. In assembling the scaffold the bands 10 are placed to encircle the pillars A and the free ends 13 of the band are inserted through the clamping elements 12 between the clamping plates 17 and the clamp portion 14. When properly encircling the post the band end 13 will then overlap the fixed end 11 in the manner illustrated. The clamping bolt 22 is tightened so as to clamp the ends of the band 10 together, thus holding the band properly engaged about the post.

The hook 24 is supported by the band 10 and is suspended therefrom. Two hook elements 24 are supported at approximately the same elevation and in parallel relation and a supporting plank structure is engaged in the hook elements 24. The scaffold or platform supporting the workmen is then superimposed upon the connecting planks.

If the posts A are relatively close together a single connecting plank may extend from one hook 24 to the next. However, if the posts or pillars are slightly farther apart it is usually preferable to use two planks arranged in overlapping relationship. As best indicated in Figures 1 and 5 of the drawing the planks are held in proper relation by clamping elements indicated in general by the numeral 32. The plank clamps 32 are similar in structure to the clamping elements 12 previously described, but are of larger size so as to accommodate the planks. The clamping elements 32 each include a rear plate 33, a front plate 34 and connecting plates

35 and 36. A clamping plate 37 extends beyond the open ends of the rectangular frame, thus produced, and ears 39 on the clamping plate 37 hold the clamping plate in proper position within the frame.

A bolt 40 extends through a boss 41 on the plate 34 of the clamping element frame and bears against the surface of the clamping plate 37, thus urging the clamping plate against one of the two planks being clamped. The two planks C are held in proper relationship by the clamping action thus provided. A handle 42 is provided on the clamping bolt 40 to assist in the clamping operation.

The operation of my scaffold support is believed obvious from the foregoing description. The belts 10 are placed at the proper elevation to encircle the posts or pillars A. The hook elements 24 are arranged in parallel relation and at approximately the same elevation. The distance between the posts is then measured. If a single plank C is of sufficient length to reach between the posts such a single plank may be employed. It is usually preferable, however, to employ the two planks C in overlapping relation, one of the planks being engaged in each hook 24. The planks are adjusted to proper length and the clamping elements 32 are tightened so as to hold the planks in proper relation. The planks are then engaged in the hook elements 24 and the scaffold platform may be supported thereby.

If the posts are in rows it is usually desirable to provide the scaffold supporting elements B on four rectangularly arranged posts. Each pair of supporting elements is connected by planks C and the platform may be formed by laying planks between the planks C supported thereby.

In accordance with the patent statutes, I have described the principles of construction and operation of my scaffold support, and while I have endeavored to set forth the best embodiment thereof, I desire to have it understood that obvious changes may be made within the scope of the following claims without departing from the spirit of my invention.

I claim:

1. A scaffold support for use in combination with vertical pillars comprising a wide flat flexible band of webbing designed to encircle each pillar of a pair of adjacent pillars and conform to the shape thereof, means for connecting the ends of the bands in pillar encircling position, and means supported thereby independently of said connecting means for connecting said bands.

55 2. A scaffold support for use in combination with vertical building pillars, said support comprising a pair of wide flat flexible bands of webbing encircling adjacent pillars and conforming to the shape thereof, means connecting the ends 60 of the band in pillar encircling position, independent bracket means supported by each band, and a rigid connecting means connecting said bracket means.

3. A scaffold support for use in combination 65 with vertical building pillars, said support comprising a wide flat flexible band of webbing arranged to encircle each pillar of two adjacent pillars and conform to the shape thereof, means connecting the ends of the band in pillar encircling position, independent hook means supported by each flexible band, and rigid connecting means connecting said hook means.

4. A scaffold support for use in combination with vertical pillars, said support comprising a 75 wide flat flexible band of webbing arranged to

encircle each pillar of a pair of adjacent pillars and conform to the shape thereof, means for clamping said band in pillar encircling position, one flat surface of said band contacting the pillar substantially throughout the periphery thereof, rigid means extending between said bands, and bracket means connecting said rigid means to said bands.

5. A scaffold support for use in combination with vertical building pillars, said support comprising a wide flat flexible band of webbing designed to encircle a pillar with the ends thereof in overlapping relation, a clamping means for clamping said overlapping ends of said band in pillar encircling position, and flat hook means of relatively inflexible material supported by said band between the band and the post.

6. A scaffold support for use in combination with vertical building pillars, said support comprising a flexible band designed to encircle each of a pair of adjacent pillars, each said band having means connected thereto for clamping said band in post encircling position, hook means selectively engageable with any portion of the encircling band secured to said band, and rigid means adjustable in length connecting said hook means.

7. A scaffold support for use in combination with building pillars comprising means encircling each of a pair of adjacent pillars, means clamping said encircling means in encircling position, rigid means connecting said encircling means, said rigid means including two rigid elements, and means holding said elements in overlapping relation, and means selectively engageable with any portion of the encircling means securing said connecting means to said encircling means.

8. A scaffold support for use in combination with vertical pillars comprising a flexible band

adapted to encircle a pillar, a box shaped clamping member connected to one end of said flexible member, a movable clamping plate in said clamping element, means for pressing said clamping plate against the other end of said band when the same is inserted therethrough to hold said band in pillar encircling position with the ends thereof overlapping, and hook means connected to said band and depending therefrom.

10 9. A clamping means for clamping a pair of parallel clamping supports in overlapping relation, said clamp comprising a substantially rectangular frame open at the ends, said rectangular frame accommodating the ends of said scaffold supporting members, a flat clamping plate slidably mounted in said frame and having a flat surface movable toward and away from said scaffold supporting elements, and means for moving said clamping plate toward said scaffold supporting elements to clamp the same together.
